UNITED STATES PATENT OFFICE.

HANS MANGOLD, OF FURTH, BAVARIA, GERMANY.

TOY FIGURE.

Application filed December 1, 1924, Serial No. 753,384, and in Germany April 16, 1924.

The present invention relates to a toy figure executing a step motion, whereby the legs forming a bow carry in their upper end a projecting arm with a crank slot member, 5 while the legs are arranged in such a manner, that a crank engages in the slot of the said member and so the movements of the figure are obtained.

Contrary to the other well known toys 10 the object of the invention described hereafter is to obtain a better effect and thus to increase the efficiency of the toy, but at the same time making it possible to manufacture the toy in a very simple and cheap way, 15 viz, by the special arrangement of a leg bow with a crank slot member and by making the latter as well as the toy figure also in a special manner.

This is obtained as follows, that the crank 20 slot member and the leg bow are connected to the frame of the driving mechanism by a resilient pin whereby the crank slot member and the leg bow are guided on this pin. Further the upward end of the crank slot 25 member engages with a slide bar movable horizontally, which carries the eyes of the figure.

The annexed drawing illustrates as example an execution of the present toy figure. 30 Fig. 1 is a side elevation partly in vertical section and Fig. 2 is an elevation from behind without the driving mechanism.

The present toy consists chiefly of a figure 35 a imitating a man or an animal arranged in a suitable manner, on the head of which the driving mechanism *d* is fixed by means of an arm *c* projecting in a backward direction. Thereby this driving mechanism is so arranged as to be suspended in a vertical direction on this arm, whereby a crank slot *l* 40 engages with a slot *k* of a crank member *f*, which is provided on the backward side with a projection *f'* bent in a right angle and carrying the legs combined in form of a bow. 45 At the downward ends of the bow are fixed weights *i*, *i'* in form of the feet to secure the steadiness of the toy figure.

According to the invention the crank slot 50 member *f*, *f'* with the leg bow *g*, *g'* fixed thereon is connected to the frame of the driving mechanism *d* by means of a resilient pin *e* engaging with the one end on the frame of the driving mechanism and with the other end on the backward projection *f'* 55 of the crank slot member. The latter is guided by a further projection *h*, which is

bent out of the crank slot member at a right angle in backward direction. The crank slot member *f*, *f'* carries a tongue-like end *m* in an upward direction, which engages 60 with a slide bar situated behind the holes for the eyes and moved horizontally in guides *o*. Also the slide bar *p* supports a projection *q* bent backwardly in a right angle into which the tongue-like end *m* is 65 slidably mounted, while on the other side of the slide bar *p* the eyes are painted at suitable locations, so that these eyes become visible when the figure is at rest.

The mode of action of the toy figure fitted 70 in the described manner is in the main like that of well known similar toys, but a better and essential additional action is thereby obtained by the movability of the eyes and according to the especial arrangement of the 75 crank slot member with the leg bow connected by means of the resilient pin *e* with the frame of the driving mechanism *d*.

Especially this flexible pin *e* renders possible that the movement from the driving 80 mechanism *d* is transmitted very easily and surely by the crank slot *l* to the crank member *f*, *f'*, because thereby the latter *f*, *f'* swings about the resilient pin *e*, i. e. the legs 85 *g*, *g'* and also the feet *i*, *i'* will be raised alternately, so that they are turned forwardly in consequence of the elasticity of the resilient pin *e*. It results therefrom, that on the one hand the step movement takes place in a sure manner, while on the other hand 90 the slide bar *p* will be actuated in a reciprocating manner by the tongue-like end *m* of the crank slot member, so that the eyes are moved alternately to the right and left 95 side.

It will be understood, that instead of arranging the eyes on a horizontally actuated slide bar they can also be arranged on a segment rocking about a fulcrum, so that by moving the segment the eyes turn in a concentrical circle, whereby the same device as described above may be used. 100

What I claim is:

1. Toy figure comprising in combination 105 a figure body shaped in a flat manner; a driving mechanism fixed on the said body; a crank driven by said driving mechanism; a crank slot member pivoted at its lower end to the frame of the driving mechanism and having a slot in which said crank operates to oscillate the member; a resilient connecting pin fixed with the one end on the 110

frame of the driving mechanism and connected with the other end to a backward projection of the crank slot member to form said pivotal connection; legs combined to a bow with feet on the lower end and mounted on the lower end of said crank slot member; holes located in the head of the figure; a slide bar having the eyes thereon and situated behind the said holes and means connected with the upper end of said crank slot member; adapted to guide and move the said slide bar.

2. Toy figure comprising in combination a figure body having a rearwardly projecting arm; a driving mechanism adapted to be suspended on said rearwardly projecting arm of the said body; a crank driven by said mechanism; a crank slot member pivoted at its lower end to the frame of said driving mechanism and containing a slot in which said crank operates; a backwardly bent projection formed at the lower end of said crank slot member; legs combined to a bow with feet fixed thereon and suspended on said projection of the crank slot member; a resilient connecting pin between said crank slot member and the frame of the driving mechanism to form said pivotal connection; a slide bar having eyes represented thereon; a head having holes representing eye sockets and means connected with the upper end of said crank slot member

to move the said slide bar having the eyes represented thereon behind the holes of the head of the figure.

35

3. Toy figure comprising in combination a figure body; a driving mechanism mounted upon the said figure body and having a crank; a crank slot member having a slot for receiving the said crank of the drive and cooperating with the crank; a backward projection formed on the lower end of said crank slot member; legs supported by said backward projection; a resilient pin fixed on the frame of the driving mechanism and adapted to connect resiliently the crank slot member with the frame of the driving mechanism; a second backwardly bent projection on said crank slot member arranged as to engage said pin and to guide the said crank slot member; a tongue-like projection formed at the upper end of said crank slot member; holes for the eyes located in the head of the figure body; a slide bar having the eyes represented thereon and situated horizontally behind the said holes; a backwardly bent projection on said slide bar which is slotted and adapted to cooperate with the tongue-like end of the crank slot member; guides arranged to receive the said horizontal slide bar.
